CLAIM

The ornamental design for an operating portion of controller for electronic game machine, as shown and described.

DESCRIPTION

FIG. 1 is a front elevational view of an operating portion of controller for electronic game machine showing my new design, a dotted line showing an external form of an operating portion of controller;

FIG. 2 is a rear elevational view thereof;

FIG. 3 is a top plan view thereof;

FIG. 4 is a bottom plan view thereof;

FIG. 5 is a left side view thereof; and,

FIG. 6 is a right side view thereof.

The broken lines are for illustrative purpose only and forms no part of the claimed design.
